UNITED STATES PATENT OFFICE.

VAN RENSSALAER LANSINGH, OF NEW YORK, N. Y.

ILLUMINATING APPLIANCE.

1,090,076.

Specification of Letters Patent. Patented Mar. 10, 1914.

Application filed April 19, 1910. Serial No. 556,418.

To all whom it may concern:

Be it known that I, VAN RENSSALAER LANSINGH, a citizen of the United States, and a resident of the city of New York, 5 State of New York, have invented certain new and useful Improvements in Illuminating Appliances, of which the following is a specification.

My invention relates to illuminating appliances intended especially to throw light upward against the ceiling. Certain features of the invention may, however, be available when the apparatus is differently placed in service.

10 In interior illumination it has been proposed to illuminate an apartment by means of opaque reflectors directed toward the ceiling and a light source, such as an incandescent lamp, placed within the reflector which conceals it from direct view. The light striking the ceiling is thoroughly diffused and gives a very soft agreeable illumination.

15 In carrying out my invention I propose to use, instead of an opaque reflector, a transparent or translucent reflector consisting, for example, of a prism glass reflector of any approved form. This reflector is to have an artificial light source within it at 20 its focus and is to be directed upward, and will throw the greater portion of the light emanating from the light source upward against the ceiling. A certain percentage of the light rays, however, pass through the 25 body of the reflector and downward into the room.

A lighting group such as has been described can be used without any additional essential elements, but in further carrying 30 out my invention I generally prefer to place the inverted prism glass reflector within a bowl of translucent, frosted or decorated glass. The light passing downward through the reflector, also passes through the outer 35 inclosing bowl and by it is further diffused or modified or colored to produce decorative effects.

40 My invention provides the diffused illumination, which is sought in appliances of this character, caused by the rays thrown 45 upward against the ceiling by the reflector, and also supplies a certain percentage of direct illumination from the rays of light which pass downwardly through the reflector and this direct illumination may, as

has been pointed out, be further modified by the outer inclosing bowl.

It is to be understood that the invention is capable of variations and may be embodied in different forms. 60

I illustrate in the accompanying drawing one of the embodiments of the invention, which I have chosen for illustrative purposes.

The drawing is a vertical diagrammatic 65 section through an appliance embodying the invention.

L designates the light source, which may conveniently be an incandescent lamp suspended from the ceiling by a rod or other 70 suitable support S.

R is an inverted prism glass reflector of any approved form so arranged that the light source is in the proper position within it. 75

B is a bowl, usually of glass, which may be entirely or partially fire-flashed, etched, frosted, or colored, or otherwise treated to give decorative effects or modify light rays passing through it. The bowl B is placed 80 outside the reflector and is supported by chains C or in any other convenient way and the reflector in turn may be supported by a bracket X resting on bowl B or in any other preferred manner. 85

According to the well-known law of prism glass reflectors, a large proportion of the light emanating from the lamp L is thrown upward against the ceiling and diffused. A remaining percentage of light passes out 90 and downward through the reflector, supplying a certain amount of direct illumination to the room. These direct light rays are further modified by passing through the outer bowl B. 95

Among the many possible modifications of the structure employed to carry out the invention, it may be pointed out that instead of a prism glass reflector, any reflector may be employed which directs upwardly a large portion of the light rays and permits a portion of the rays through the body of the reflector and directly downward into the room or through the inclosing bowl B. For instance a reflector or shade of 105 opalized glass, or one coated on the outside with translucent light colored enamel, or a bowl exteriorly frosted with a polished inner surface, may be substituted for the prismatic reflector R. The inclosing bowl B 110

need not be a simple translucent or decorated glass bowl, but may be a composite structure composed of different panels of translucent, frosted, etched or decorated 5 glass, or other suitable transparent or translucent material.

I claim:

1. In an indirect-lighting appliance, a light source, an upwardly facing translucent 10 reflector surrounding the source, an upwardly facing diffusing bowl surrounding the reflector, and means for supporting said reflector and said bowl by their outer edges from above.

2. An indirect-lighting appliance comprising a light source and a member for supporting the same from above, an upwardly-facing translucent reflector surrounding said source, an upwardly-facing diffusing bowl surrounding said reflector 20 and supporting means independent of the aforesaid supporting member extending from above to the outer edges of said bowl and said reflector.

VAN RENSSELAER LANSINGH.
